(57) **CLAIM**

The ornamental design for a tablet computer, as shown and described.

DESCRIPTION

FIG. 1 is a front perspective view of a tablet computer showing my new design in a first embodiment;

FIG. 2 is a rear perspective view of the first embodiment of my new design;

FIG. 3 is a front view of the first embodiment of my new design;

FIG. 4 is a rear view of the first embodiment of my new design;

FIG. 5 is a left side view of the first embodiment of my new design;

FIG. 6 is a right side view of the first embodiment of my new design;

FIG. 7 is a top view of the first embodiment of my new design;

FIG. 8 is a bottom view of the first embodiment of my new design;

FIG. 9 is a front perspective view of the tablet computer in a second embodiment;

FIG. 10 is a rear perspective view of the second embodiment of my new design;

FIG. 11 is a front view of the second embodiment of my new design;

FIG. 12 is a rear view of the second embodiment of my new design;

FIG. 13 is a left side view of the second embodiment of my new design;

FIG. 14 is a right side view of the second embodiment of my new design;

FIG. 15 is a top view of the second embodiment of my new design; and,

FIG. 16 is a bottom view of the second embodiment of my new design.
